INSECT REPELLENTS

Paul D. Bartlett, Weston, and Sidney D. Ross,
North Adams, Mass., assignors to the United
States of America as represented by the Secre-
tary of the Army

No Drawing. Application January 7, 1949,
Serial No. 69,831

8 Claims. (Cl. 167—33)

1

This invention relates to insect repellents.

We have found that the application of an ester of furylacrylic acid and an aliphatic alcohol having at least 4 carbon atoms, when applied to the human skin or a fabric, effectively repels insects, particularly *Aedes aegypti* and *Anopheles quadrimaculatus*.

The esters of furylacrylic acid contemplated in our invention have the structural formula

wherein R is the residue of an aliphatic alcohol having at least four carbon atoms.

Tests to measure the repellency of the above-mentioned compounds against insects by skin application were conducted by smearing the compound on the arms of test personnel, who then thrust their arms into cages containing insects. The arms were exposed for 30-minute intervals at 3 minutes each until the first insect bite.

Tests to measure the repellency of fabrics impregnated with the above-mentioned compounds against insects were conducted by uniformly impregnating mercerized cotton hose with the compound at a rate equivalent to 3.3 gms. per sq. ft., drawing the dried hose over the arms of test personnel, who then thrust their covered arms into cages containing insects for 1 to 2 minutes.

Examples of aliphatic alcohols with at least 4 carbon atoms, whose esterification products with furylacrylic acid have insect-repellent properties, are, for instance, saturated compounds such as sec-butyl alcohol and amyl alcohol, unsaturated compounds such as methallyl alcohol, and alkoxy compounds such as cellosolve (2-ethoxy-ethanol).

The following table illustrates the results obtained by the above test methods against *Aedes aegypti* and *Anopheles quadrimaculatus*, as examples of insects against which the invention is applicable, by using compounds in accordance with the present invention.

Material	Insect Repellency upon Application to Skin		Insect Repellency of Impregnated Fabric against <i>Aedes aegypti</i>
	<i>Aedes aegypti</i>	<i>Anopheles quadrimaculatus</i>	
Sec-butyl ester of furylacrylic acid.	Mins. 188	Mins. 62	over 5 days.
Amylester of furylacrylic acid.	over 120	198	over 10 days.
Methallyl ester of furylacrylic acid.			Do.
Cellosolve ester of furylacrylic acid.	207	42	Do.

For ease of application, the furylacrylic acid esters contemplated by the present invention may

2

be incorporated in a suitable inert liquid or solid carrier such as mineral oil, alcohol, petrolatum, etc. For facile and uniform fabric impregnation, they may be applied in an inert solvent, such as alcohol, ether, etc.

Having thus fully described our invention, we claim:

1. An insect repellent fabric comprising fabric impregnated with an ester of furylacrylic acid and of an aliphatic alcohol having 4 carbon atoms in its molecule.
2. An insect-repellent fabric comprising fabric impregnated with the methallyl ester of furylacrylic acid.
3. An insect-repellent fabric comprising fabric impregnated with the Cellosolve ester of furylacrylic acid.
4. An insect-repellent composition comprising in an inert non-gaseous organic carrier an ester of furylacrylic acid and of a saturated aliphatic alcohol having 4 carbon atoms in its molecule.
5. An insect-repellent composition comprising the sec-butyl ester of furylacrylic acid in an inert non-gaseous organic carrier.
6. An insect-repellent composition comprising the methallyl ester of furylacrylic acid in an inert non-gaseous organic carrier.
7. An insect-repellent composition comprising the Cellosolve ester of furylacrylic acid in an inert non-gaseous organic carrier.
8. An insect-repellent composition comprising an ester of furylacrylic acid and of an aliphatic alcohol having four carbon atoms in its molecule in a non-gaseous inert organic carrier.

PAUL D. BARTLETT.
SIDNEY D. ROSS.
